Application July 8, 1935, Serial No. 30,310

17 Claims. (Cl. 273—86)

This invention has to do in a general way with game and amusement apparatus and is more particularly related to a novel form of amusement device which is designed to simulate a race such as a horse-race. In other words, the device contemplated by this invention embodies a miniature field or track provided with a plurality of lanes along which a corresponding number of racing pieces such as miniature horses are adapted to travel at varying rates so that one of the racing pieces may reach the forward or winning end of the field in advance of the others.

It is a primary object of this invention to produce a device of the class described in which the entire operation thereof is automatic. In other words, our invention contemplates an amusement device of the class described which is designed to be controlled by a single manually operated switch which may or may not be associated with a coin actuated means for controlling the same.

It is a further object of this invention to produce a device of the class described in which the rate of movement of the different racing pieces along the field is automatically changed each time the game is played and in this same connection our invention contemplates a means whereby all of the racing pieces are automatically returned to their starting position as soon as one of the pieces has reached a predetermined point in its course of travel. In this same connection our invention contemplates means for providing a sustained indication such as an electric light which is illuminated as soon as the race is won and remains lighted for a substantial period of time so as to indicate which piece won the race even after all of the pieces have been returned to their starting position.

It is a still further object of this invention to provide a device of the class described with a scoring unit to indicate at the start of the race the score which will be made by each horse in the event such horse wins the race and in this same connection our invention contemplates means for automatically changing the scoring setup for the various horses each time the game is played.

It is a further noteworthy feature of this invention that the entire operation thereof is controlled electrically so that all of the operations and movements take place with maximum positiveness and rapidity.

The details in a preferred form of our invention together with other objects attending its production will be best understood from the fol-

lowing description of the accompanying drawings which are chosen for illustrative purposes only and in which

Fig. 1 is a plan view illustrating the general arrangement of the miniature racing field together with the lighting and scoring units in a preferred embodiment of our invention;

Fig. 2 is a sectional elevation taken along the line 2—2 of Fig. 1;

Fig. 3 is a sectional elevation taken along the line 3—3 of Fig. 2, and illustrating the mechanism employed in retracting the pieces across the field;

Fig. 4 is a fragmentary end section taken along the line 4—4 of Fig. 3;

Fig. 5 is an enlarged fragmentary sectional elevation taken along the line 5—5 of Fig. 2, illustrating details in the construction of the electromagnetic clutch and pulley assembly for advancing the racing pieces;

Fig. 6 is an enlarged fragmentary sectional elevation taken along the line 6—6 of Fig. 1, illustrating details in the construction of a light switch relay assembly and the scoring drum control means;

Fig. 7 is a sectional elevation taken along the line 7—7 of Fig. 6 showing further details in the construction of the scoring drum;

Fig. 8 is an elevation taken along the line 8—8 of Fig. 6 illustrating further details in the construction of the light switch mechanism;

Fig. 9 is an enlarged end elevation taken along the line 9—9 of Fig. 2 illustrating details in the construction of the driving mechanism as well as some details in the construction of the timing means for controlling the intermittent movements of the respective racing pieces;

Fig. 10 is a fragmentary elevation taken along the line 10—10 of Fig. 9 illustrating further details in the construction of a control timing switch contemplated by this invention;

Fig. 11 is an enlarged fragmentary elevation taken through the case at a different plane from Fig. 2 and illustrating the details in the construction of the preferred system of relay switches which we employ to start, reverse, and stop the operation of the racing pieces;

Fig. 12 is a plan view taken along the line 12—12 of Fig. 2 illustrating one preferred form of switch control mechanism which we employ to vary the relation between the two timing mechanisms which govern the control of current to the electromagnets on the advancing clutches;

Fig. 14 is a wiring diagram illustrating the electrical relation between the different parts of the apparatus contemplated by this invention.

Referring now to the drawings with particular reference to Figs. 1 and 2, reference numeral 11 indicates a case or housing which is shown as being provided with a glass cover 12 and has a deck or board of play 13 mounted therein below the cover 12. Reference numeral 14 indicates a light and score panel which is positioned in the housing ahead of the deck 13.

The deck 13 is shown as being provided with a plurality of lanes 15 arranged in parallel relation thereon, such lanes formed by guide flanges 16. 15 The lanes are in the nature of slots which extend through the deck member each of such slots containing a racing piece generally indicated by reference numeral 17. The racing pieces 17 are made to simulate a figure such as that of a horse 20 and rider and include a standard or post 18, an intermediate portion of which is secured in any suitable manner to a belt member 19. Each of the belts, there being one for each racing piece, extends over a pair of pulleys 20 and 21 which 25 are rotatably mounted upon shafts 22 and 23 respectively. The shafts 22 and 23 are supported by suitable bearings which are secured in any preferred manner to the interior of the housing as indicated at 25 and 25' in Figs. 3 and 5 respectively.

The shafts 22 and 23 are adapted to be continuously rotated in opposite directions as indicated by the arrows A and B (Fig. 2) during the operation of the machine and since connection of the pulleys 20 with the shaft 22 is effective to rotate or drive the belt 19 in a direction which pulls the racing pieces 17 forward, we have termed the shaft 22 the "advancing shaft" and the pulleys thereon the "advancing pulleys". Also since engagement of the pulleys 21 with the shaft 23 is effective to rotate such pulleys in a belt retracting direction, we have termed such shaft pulleys "retracting members".

For the purpose of imparting this opposite directional rotation to the two shafts 22 and 23, we show such shafts as being provided with sprocket wheels 26 and 27 which are interconnected by means of a crossed sprocket chain 28. One of the shafts, shown as the shaft 23, is also provided 45 with an additional sprocket wheel which is adapted to be driven through the medium of a chain 29 from a drive sprocket 30 in a reduction gear unit generally indicated by reference numeral 31.

From the foregoing general description it will 55 be seen that the racing pieces 17 are adapted for movement back and forth across the deck or field of play depending upon which set of pulleys is engaged with the corresponding rotatable shaft.

60 In addition to the racing pieces and their corresponding track, the visible portion of the apparatus includes the light and score indicating panel 14 which is provided with a plurality of light windows 35 each corresponding to one of 65 the lanes and racing pieces and a plurality of score windows 36 each of which also correspond to one of the racing pieces and lanes.

The operation of the apparatus is as has been 70 previously pointed out, entirely automatic except for one manual operation which involves the closing of the starting switch. This starting switch may be of any desired type of push button or a coin actuated plunger of the type indicated by reference numeral 37. When this plunger or 75 push button is actuated the following operations

take place. First the light in one of the windows 35 which corresponds to the particular racing piece which won the previous race is disconnected and at substantially the same time all of the racing pieces start their intermittent or step by step forward movement across the field in their respective lanes. Simultaneous with this operation the score numbers behind the windows 36 are changed to show the score which each horse will make in the event it wins the race. The race then 10 continues until one of the horses reaches the winning point at which time the light in the window corresponding to that particular horse is automatically lighted and immediately all of the racing pieces start their rearward movement to 15 the starting point. This rearward movement in the racing pieces continues until each one has reached the starting line at which time all of the electrical circuits which govern the operation of the machine with the exception of the circuit 20 to the light in the widow indicating the winning horse are disconnected. This light remains lighted until the machine is played again or if desired another switch such as a time actuated switch may be provided for the purpose of disconnecting this light after the machine remains unplayed for a predetermined interval of time.

We will now describe the details in the mechanism whereby these various operations and indications are obtained.

Referring first to Fig. 2 it will be observed that all of the racing pieces 17 have been retracted to their starting position in the manner generally described above. The source of power for moving the racing pieces in either direction 35 is shown as comprising an electric motor 40 which is provided with a shaft 41 having a pulley 42 thereon (see Fig. 9), such pulley being connected through a belt 43 to a driven pulley 44. The driven pulley 44 is mounted upon a shaft 40 45 which in turn forms a part of the reduction gear unit 31. The motor is supplied with electrical energy from a suitable source of power through a system of relay switches to be described later in the specification whereby its 45 operation is automatically controlled from the switch or coin operated plunger 37 referred to above.

Referring now to Figs. 3 and 4 which illustrate the details in the preferred form of mechanism which we employ to effect the retractive or rearward movement of the racing pieces, it will be observed that the pulleys 21 which, as has been herein above pointed out, are loosely mounted upon the shaft 23, are provided with 55 friction clutch faces 50. Associated with these clutch faces and rigidly keyed to the shaft 23 are a corresponding number of clutch plates 51.

For the purpose of moving the pulleys and the corresponding clutch faces into frictional engagement with the clutch plates 51 whereby the pulleys are rotated with the shaft, we provide each pulley with a hub member 52, such hub member being provided with grooves 53 which in turn are engaged by the slots at the upper 65 ends of corresponding fork or clutch bars 54. The lower ends of these clutch bars, there being one for each pulley, are secured to a clutch actuating rod 55 such rod being supported by suitable bearings such as are indicated at 56 so 70 that it may have sliding movement. The end of the clutch bar 55 is secured in any suitable manner such as by means of a pin and slot connection 57 to a lever member 58 which in turn is supported through the medium of a leaf spring 75

59 from a bracket 60 secured to the interior of the housing.

This lever member is associated with a solenoid or electromagnet 61 such magnet being adapted for energization from a source of power through the medium of suitable relay switches to be hereinafter described so that all of the pulleys and corresponding clutch members are engaged simultaneously to effect a retractive movement of all of the racing pieces at once. When all of the racing pieces reach their starting point at which they engage corresponding stop members they are effective, through the medium of suitable parallel switches and relays, to open the circuit to the motor 40 whereby the operation of the machine is stopped.

For the purpose of effecting this last mentioned control we employ a plurality of contact switches indicated by reference numeral 65
20 each of which is associated in suitable relation with a corresponding racing piece. All of these switches are connected in parallel with the relay that controls the delivery of power to the motor and each switch is arranged so that it is normally in a closed position. For the purpose of opening these switches we provide them with lever members indicated by reference numeral 66, each lever member having a projection 64 on its upper end which extends into the path
25 30 of the standard or supporting post 18 on the corresponding racing piece.

As each racing piece engages its lever member 63 it is effective to open the corresponding switch 65 and remain stationary in such position, the pulley in the corresponding belt member slipping until the operation of the machine is stopped. With the switches 65 all connected in parallel, it will be observed current will flow through this circuit until the last switch is opened so that the operation of the machine continues until the last racing piece has reached its starting point at which time the last switch is opened and the operation of the machine is thereby stopped.

45 In Fig. 5 which illustrates the details in the mechanism for effecting the forward or advancing movement of the racing pieces, it will be observed that each of the advancing pulleys 29, like the retracting pulleys 21, is provided with 50 a clutch face 50' associated with a clutch disc 51' which is keyed to the shaft. Also the pulleys 20 are provided with hubs 52' which have grooves 53' adapted to receive the forked or slotted upper end of a clutch control bar 54'.

Since the principal objective during the forward movement of the racing pieces is to simulate a race, it is necessary that the individual clutch members on the advancing pulleys 29 be adapted for individual and repeated actuation. It is also important that the momentary or intermittent period during which the clutch members are engaged should be varied with respect to each other during each race and should also be varied with respect to each other between the different races so that the results of the different races will not repeat themselves. For the purpose of individually engaging the clutch members it will be observed that each lever member 54 is supported by a spring member 65 and a suitable supporting bracket 66 and is associated with an individual solenoid or electromagnet 67. These individual electromagnets 67 are adapted to be intermittently and repeatedly energized from a suitable source of power so as to individually engage the clutch over different intervals of time. The

control of current to the different magnets 67 is effected through a timing mechanism the details in the construction of which are best illustrated in Figs. 2, 9 and 10 and which will now be described.

Referring first to Figs. 2 and 9, reference numeral 70 indicates the stationary supporting disc which is provided with a plurality of circumferentially spaced contact switches 71. The switches 71 correspond in number to the number of electromagnets 67 which are associated with the advancing pulleys 20 and each switch is connected in series with its corresponding electromagnet. Mounted upon a shaft 12 of the reduction gear unit 31 and concentrically disposed within the area defined by the switches 71 is a rotor member 73, such rotor member having a projection 74 thereon which is adapted to individually engage each of the contact switches 71 during the rotation of the rotor.

Assuming that each of the switches 71 were connected with a source of electrical energy, it will be seen that when the rotor 73 is revolved at a constant speed the electromagnets would be successively energized over equal lengths of time and the racing piece corresponding to the first switch engaged would be the first to reach the finish line. As has been previously pointed out, however, it is a feature of this invention that an element of suspense is introduced in the outcome of the race and in order to do this it is necessary to vary the interval of time during which current is supplied to the respective contact switches 71 while they are engaged by the projection 74. It is also important that the ratio with which the current is distributed among the different contact switches be varied for each race.

For the purpose of accomplishing this last mentioned objective, we employ a second timing mechanism which we term a "control timer" such mechanism being illustrated generally by reference numeral 76. This timing mechanism is shown as comprising a rotor 77 which is rotatably mounted upon a shaft 78 supported by a standard 79 on top of the reduction gear housing 31. The rotor 77 is normally adapted to be driven from the shaft 78 through the medium of a friction clutch member indicated at 80 and is spring pressed against the clutch member by means of a compression spring 81.

For the purpose of rotating the shaft 78 and its associated elements, the shaft is provided with a pulley member 83 over which a belt 84 travels such belt being driven by means of the pulley 85 which is driven from the reduction gear unit 31.

The rotor 77 is shown as being provided with a plurality of projections 87, such projections being of different circumferential lengths and of various spacing with respect to each other and being of a radius such that they will engage and close a contact switch generally indicated by reference numeral 90. This contact switch is shown as being supported upon a post or bracket 91 which is also secured to the top of the reduction gear unit and the elements of the contact switch are connected to the source of energy and to the respective contact switches 71 in the first timing unit described above which delivers current to the advancing solenoid. 77

From this arrangement it will be seen that in order to energize any one of the advancing solenoids, it is necessary that the contact switch 71 and the contact switch 90 both be closed. From this arrangement it will also be seen that since 75

the length of the contact members on the rotors 77 are of various lengths and various spacing and further in view of the fact that the two rotors are operated in different speed ratios with respect to each other, that the time intervals during which current is supplied to the advancing solenoids is always changing during a single operation of the machine.

It was also pointed out as another object of this invention to provide means for varying the relation with which the advancing clutches are actuated with respect to each other each time the machine is operated. In other words our invention contemplates means for changing the relation between the two timing rotors for each operation of the machine. In the preferred form of our invention we accomplish this by momentarily stopping the operation of the rotor of the control timer 77 at the time the operation of the machine is started and at the same time permitting the rotation of the rotor 74 to continue.

Since the rotor 77 is, as pointed out above, loosely mounted upon the shaft 78 we accomplish this by means of a solenoid actuated brake generally indicated by reference numeral 100. This brake is shown as comprising a lever member 101 positioned so that its forward end may be thrown down into engagement with the rotor 77 by means of a solenoid or electromagnet 102. Various means may be employed for momentarily energizing the electromagnet 102 but it is a noteworthy feature of this invention that such means be constructed so that the period of energization of this magnet varies an indeterminate amount for each race. One preferred form of this mechanism is indicated generally by reference numeral 105 in Fig. 2 and the details thereof are further illustrated in Figs. 12 and 13.

Referring to Figs. 2, 12 and 13, reference numeral 106 indicates a contact switch which is mounted on the bottom of an inclined plate member 107, such switch being normally held in its open position by means of a weighted ball 108 which rests upon a switch control plate 106'. The switch 106 is connected between a source of energy (not shown) and the electromagnet or solenoid 102. The ball 108 is adapted to be thrown forwardly and upwardly across the inclined plate 107, so as to permit the closure of the contact switch 106, by means of an electromagnetic kicker generally indicated at 110.

The duration of time over which the contact switch remains closed and the rotor 77 remains locked depends upon the period of time over which the ball travels on the inclined plate 107 before returning to the switch control plate 106'. This interval of time is varied between the different operations by employing an odd shaped area through which the ball must travel thereby changing the length of its travel depending upon the particular manner and direction in which it is started by the electromagnetic kicker 110. In this form of our invention we show the area in which the ball must travel as being controlled by a boundary wire 112 supported on pins or screws 113 and arranged so that the distance from the kicker to the wire is different along different lines of travel.

The energization of the electromagnetic kicker 110, as well as the extinguishment of the light and the setting up of the score indicator referred to above, must be accomplished when the game is first started in operation and for the purpose of energizing these three elements, we employ a single switch and drum assembly generally indi-

cated by reference numeral 120. This switch and drum assembly, the details in the construction of which are best shown in Figs. 2 and 9, consist of a drum member 121 which is loosely mounted upon the shaft which carries the rotor 73. The drum member is shown as being provided with an enlarged disc 122 which is in frictional engagement with the clutch plate 123 mounted on the end of the rotor member 73. Since it is necessary to impart only a single rotation to the drum each time the machine is started in operation, the disc and the drum are normally locked against movement by means of a locking lever 124 having a finger 125 normally adapted for reception in a notch 126 in the periphery of the disc. This locking finger is supported by a spring and bracket assembly 127 adjacent an electromagnet or solenoid 128 which is adapted to be energized when the manually actuated switch or push button is closed to start the operation of the machine. The momentary energization of this solenoid is effective to retract the finger 125 and permit the friction clutch 123 to rotate the disc 122 and its associated drum.

The drum 121 is shown as being provided with projecting segments 130, 131 and 132 such segments being adapted for engagement with contact switch members 130', 131' and 132'. The switch member 130' is connected to the kicker solenoid 110 and the switches 131' and 132' are connected to the light release mechanism and the score counter clutch which will be hereinafter described. It will thus be seen that during such time as the projection 130 is engaged with the contact switch member 130' energy is delivered to the kicker solenoid 110 which impels the ball 108 off of the switch control plate and thereby energizes the brake which engages the rotor member 77 and changes the angular position of the rotor 77 with respect to the rotor 73 which continues to rotate in the meantime.

Referring now to Figs. 2, 6, 7 for details in the construction of the scoring drum unit herein above referred to, reference numeral 130'' indicates an elongated drum or cylinder which is mounted upon a shaft 131'' supported in bearings 132'' beneath the panel 14. This drum 130'' is positioned directly below the windows 36 and is provided with a plurality of rows of numbers indicated at 133 which are situated so that one number in each row appears beneath the corresponding window 36 when the drum is stationary.

For the purpose of imparting rotation to the drum we provide the shaft 131'' with a clutch plate 135 which is rigidly secured thereto and is adapted for engagement by a pulley 133' loosely mounted on the shaft and connected through the medium of a belt 134 with another pulley 135' on the reduction gear unit. The loose pulley 133' has a hub member 137 grooved as indicated at 138 to receive an actuating fork 139 which in turn is secured to the top of an electromagnetically actuated lever 140. This lever 140 is provided with an extension 141 which has a finger portion adapted for reception between teeth 142 formed on a sprocket wheel 145 secured to the shaft 131''. This latter mechanism is effective to lock the drum in a stationary position after it has been rotated.

When the electromagnet 133' is energized by the engagement of the contact switch 132' referred to above, it is effective to simultaneously withdraw the finger 141 and engage the clutch member so that the drum is rotated during such

time as the contact switch 132' is engaged by the projection 132 on the main control drum 121.

The switch mechanism whereby the lights indicating the winner of the race are energized and disconnected are best illustrated in Figs. 2, 6 and 8. Referring first to Fig. 2, reference numeral 150 indicates a plurality of switch levers positioned beneath the finished line or finish point corresponding to each horse. Each of these levers is adapted to be engaged by the supporting post or standard 18 and when any one of these levers is engaged it is effective to close a corresponding contact switch member 151 which completes an electrical circuit through an electromagnet 152 (see Fig. 6). The energization of this electromagnet 152 is effective to withdraw a lever member 153 rearwardly into a position at which it is locked by a spring finger 154. The rearward movement of this lever is, in turn, effective to close and hold in closed position a contact switch member 155 which is connected between the source of energy and an electric light 156 positioned beneath the window 35 corresponding to the particular racing piece which has engaged the switch.

For the purpose of opening the switch 155 and thereby distinguishing the particular light which has been energized, we employ a transverse bar member 160 (see Figs. 6 and 8) which is provided with a plurality of cam plates 161 each being positioned above the locking finger 154 corresponding thereto. The bar 160 and the corresponding cam member are adapted to be drawn in the general direction of the arrow C (see Fig. 8), and thereby depress the particular locking finger 154 to release the switch 155 corresponding thereto, by means of an electromagnet and a lever member indicated at 163 and 164 respectively. This electromagnet 163 is energized through the contact switch 131' in the manner described above.

Fig. 11 illustrates a preferred system of relay switches which may be employed for controlling the starting, reversing and stopping operations herein above referred to. This system of switches may be mounted at any desired point within the case or housing and is shown as comprising a starting solenoid 170 adapted to be energized through the medium of the manually actuated starting switch 37. When this electromagnet 170 is energized it raises a lever member 171 thereby closing two identical contact switches situated one behind the other and indicated in Fig. 11 by reference numerals 172 and 172'.

The two switches 172 and 172' are connected to the motor and to the timing circuit which delivers energy to the advancing magnets respectively. As soon as the switches 172 and 172' are closed the motor starts in operation and the advancing magnets are energized repeatedly in the manner referred to above bringing the racing pieces downwardly across the field. The finger 171 is locked in a switch closing position by means of a locking finger 174 so that this operation continues until the locking finger 174 is pulled forwardly to release the finger 171. This operation is effected by means of another electromagnet 175 which is connected with each of the switches 151 and is thereby energized as soon as one of the racing pieces reaches the finish point.

When the finger 171 is released and dropped to the full line position shown in Fig. 11, it is effective to open the circuit to the advancing magnets and to the motor and at the same time close the

circuit to the retracting magnet or solenoid 61 through the upper switch indicated at 176.

Since the release of the lever 171 is effective to open the circuit to the motor and since the motor must continue to operate during the retraction of the racing pieces, it is necessary to provide switch means for maintaining the circuit to the motor closed after the lever member 171 has been released. This is accomplished by providing an additional switch 178 which is connected in parallel with the switch 172 to the motor circuit. The switch 178 is adapted to be closed through the medium of a lever member 179 and a solenoid 180 such solenoid being connected in series with the circuit of the parallel switches 65 so that it is energized as soon as any one of the racing pieces leaves its starting position. It will thus be seen that the switch 178 "standsby" in a closed position to supply current to the motor as soon as the switch 172 is opened. The retracting switch 176 is also connected in series through the switch 178 to supply current to the reversing electromagnet.

Since the electromagnet 180 is connected in series with the parallel switches 65 at the starting line, it will be seen that this magnet remains energized until all of the racing pieces have been returned to the starting position. Immediately as the last racing piece engages its corresponding switch 65 the circuit is broken and the electromagnet releases the lever member 179 thereby opening the only remaining circuit to the motor and to the reversing or retracting solenoid.

The operation of the device will be best understood by reference to the wiring diagram of Fig. 14 which illustrates the electrical circuit for connecting and operating the various elements described above, in which the letters "DC" indicate a battery, or any other suitable source of direct current or rectified alternating current for energizing the lights and the various solenoid relays of the apparatus. Reference numeral letters "AC" indicate a source of alternating current for supplying power to the motor.

In operation the switch 37 is momentarily closed by manual operation thereby completing a circuit through the electromagnet 170 and the electromagnet 128. The energization of the electromagnet 170 is effective to close the switch 172 and the switch 172'.

The closure of the switch 172 connects the motor 40 with the source of power starting the motor and its associated reduction gear mechanism which includes the drum 121 and the disc 122 which is connected thereto.

The electromagnet 128 having been energized by the closure of the switch 37, the locking finger 124 is withdrawn thereby permitting the drum 121 to rotate.

As the drum 121 rotates it is effective to successively close the switches 130', 131' and 132', thereby energizing the kicker electromagnet 110, the light release magnet 163 and the score drum control magnet 139' respectively.

The first of these operations closes the control switch 106 which energizes the solenoid 102 thereby applying the brake to the control timer drum 11.

The closure of switch 131' energizes the light release solenoid 163 thereby extinguishing the light which has been energized by the previous operation.

The closure of switch 132' energizes the electromagnet 139' which releases the score drum lock and applies the score drum clutch in the manner pointed out herein above, thereby setting up the

scores for the various horses in the race now in progress.

As the ball 108 rolls back into position the control timer 77 again starts to rotate and since the switch 172' has been closed, current is supplied through the control timer 77 and the feeding timer switches 71 to the successive advancing solenoids 67, thereby applying the advancing clutches repeatedly and intermittently to affect progressive advancing movement of the racing pieces across the field.

Also as soon as the first racing piece leaves its starting point the corresponding switch 65 at that point closes thereby establishing an electric circuit through the solenoid 180 and closing the switches 178 and 178'.

As has been herein above indicated the switch 178 is merely connected in parallel across the motor circuit and is not effective at this time to do any thing more than "stand by" ready to supply power to the motor when the switch 172 is opened. Also since the switch 178' is connected in series with the switch 176 it does not become effective until the switch 176 is closed.

As the racing pieces progress downwardly across the field the first one to reach the finish point engages its corresponding switch 151 thereby establishing an electric circuit through the electromagnet 175 which retracts the lever member 174 and releases the lever member 171.

The releasing of lever member 171 is effective to close the switch 176 and open the two switches 172 and 172'. The circuit to the advancing solenoids is thereby opened and the circuit to the 35 retracting magnet is closed, the motor in the meantime receiving its power through the switch 178, the retraction of all of the pieces begins. Each of the switches 151 is also connected in series with its corresponding light relay 152 so that the closure of this switch is effective to energize one of the relays 152 which in turn closes the corresponding switch 155 and energizing the light 156 which corresponds to the racing piece which was first to reach the finish point. When the light switch 155 is closed it is locked in closed position by means of the mechanism described and illustrated in connection with Fig. 6.

As the racing pieces are retracted each successive piece when it reaches the starting point engages its corresponding switch 65 opening such switch and these switches being connected in parallel it will be seen that the last racing piece to be retracted to its starting position is effective to completely open the circuit. Since the circuit which includes the parallel switches 65 also includes the solenoid 180, it will be seen that the breaking of this circuit is effective to disconnect the solenoid 180 thereby releasing the lever member 179 and thus opening the only remaining switch which connects the motor and the source of power. This action also opens the retracting control switch 178' and since the supply of power to the retracting solenoids is dependent upon this switch as well as the switch 176 it will be seen that all of the operating parts in the circuit are thus disconnected from their corresponding sources of power with the exception of the light 156. The circuit to these lights is opened by the action of the electromagnet 163 in the manner which has been previously described.

It is to be understood that while we have herein described and illustrated one preferred form of our invention, that the invention is not limited to the precise construction explained above but includes within its scope whatever changes

fairly come within the spirit of the appended claims.

We claim as our invention:

1. In an amusement device of the class described, the combination of: a deck having a plurality of lanes thereon; shafts rotatably supported adjacent the ends of said lanes; a plurality of aligned sets of pulleys mounted on said shafts in parallel relation with said lanes; a belt member extending over each set of pulleys; a racing piece in each lane attached to a corresponding belt member; means for rotating one of said shafts in a belt advancing direction; a plurality of clutch elements secured to said belt advancing shaft and normally out of engagement with the respective pulleys; means for repeatedly and intermittently engaging the respective clutch elements with their respective pulleys independently of each other; means for varying the intervals of operation of the respective clutch engaging means thereby varying the rate of advancement of the respective belts and pieces; means for rotating the other of said shafts in a belt retracting direction; clutch means secured to said retracting shaft and adapted for engagement with the respective pulleys thereon; and means for simultaneously engaging all of said retracting clutches.

2. In an amusement device of the class described, the combination of: a deck having a plurality of lanes thereon; shafts rotatably supported adjacent the ends of said lanes; a plurality of aligned sets of pulleys mounted on said shafts in parallel relation with said lanes; a belt member extending over each set of pulleys; a racing piece in each lane attached to a corresponding belt member; means for rotating one of said shafts in a belt advancing direction; a plurality of clutch elements secured to said belt advancing shaft and normally out of engagement with the respective pulleys; means for repeatedly and intermittently engaging the respective clutch elements with their respective pulleys independently of each other; means for varying the intervals of operation of the respective clutch engaging means thereby varying the rate of advancement of the respective belts and pieces; means for rotating the other of said shafts in a belt retracting direction; clutch means secured to said retracting shaft and adapted for engagement with the respective pulleys thereon; and means for simultaneously engaging all of said retracting clutches and at the same time rendering said advancing clutches inoperative.

3. In an amusement device of the class described, the combination of: a deck having a plurality of lanes thereon; shafts rotatably supported adjacent the ends of said lanes; a plurality of aligned sets of pulleys mounted on said shafts in parallel relation with said lanes; a belt member extending over each set of pulleys; a racing piece in each lane attached to a corresponding belt member; means for rotating one of said shafts in a belt advancing direction; a plurality of clutch elements secured to said belt advancing shaft and normally out of engagement with the respective pulleys; electromagnetic means for individually engaging said clutch elements with their respective pulleys; and contact means for repeatedly and intermittently connecting the respective electromagnetic means with a source of electric energy.

4. In an amusement device of the class described, the combination of: a deck having a plurality of lanes thereon; shafts rotatably supported adjacent the ends of said lanes; a plurality of aligned sets of pulleys mounted on said shafts in parallel relation with said lanes; a belt member extending over each set of pulleys; a racing piece in each lane attached to a corresponding belt member; means for rotating one of said shafts in a belt advancing direction; a plurality of clutch elements secured to said belt advancing shaft and normally out of engagement with the respective pulleys; electromagnetic means for individually engaging said clutch elements with their respective pulleys; contact means for repeatedly and intermittently connecting the respective electromagnetic means with a source of electric energy; and means for varying the time intervals during which the respective electromagnetic means are energized. 5
5. In an amusement device of the class described, the combination of: a deck having a plurality of lanes thereon; shafts rotatably supported adjacent the ends of said lanes; a plurality of aligned sets of pulleys mounted on said shafts in parallel relation with said lanes; a belt member extending over each set of pulleys; a racing piece in each lane attached to a corresponding belt member; means for rotating one of said shafts in a belt advancing direction; a plurality of clutch elements secured to said belt advancing shaft and normally out of engagement with the respective pulleys; electromagnetic means for individually engaging said clutch elements with their respective pulleys; and means for intermittently energizing the respective electromagnets comprising, contact means conductively connected with the respective electromagnets, means for individually and intermittently engaging the respective contacts, switch means conductively connecting said contacts with a source of electrical energy, and means for intermittently closing and opening said switch means during the intermittent engagement of said contacts. 10
6. In an amusement device of the class described, the combination of: a deck having a plurality of lanes thereon; shafts rotatably supported adjacent the ends of said lanes; a plurality of aligned sets of pulleys mounted on said shafts in parallel relation with said lanes; a belt member extending over each set of pulleys; a racing piece in each lane attached to a corresponding belt member; means for rotating one of said shafts in a belt advancing direction; a plurality of clutch elements secured to said belt advancing shaft and normally out of engagement with the respective pulleys; electromagnetic means for individually engaging said clutch elements with their respective pulleys; and means for intermittently energizing the respective electromagnets comprising, contact means conductively connected with the respective electromagnets, means for individually and intermittently engaging the respective contacts, switch means conductively connecting said contacts with a source of electrical energy, means for intermittently closing and opening said switch means during the intermittent engagement of said contacts, and means for automatically changing the relation between the timing of said switch closing means and the timing of said contact closing means. 15
7. In an amusement device of the class described, the combination of: a deck having a plurality of lanes thereon; shafts rotatably supported adjacent the ends of said lanes; a plurality of aligned sets of pulleys mounted on said shafts in parallel relation with said lanes; a belt member extending over each set of pulleys; a racing piece in each lane attached to a corresponding belt member; means for rotating one of said shafts in a belt advancing direction; a plurality of clutch elements secured to said belt advancing shaft and normally out of engagement with the respective pulleys; electromagnetic means for individually engaging said clutch elements with their respective pulleys, and means for intermittently energizing the respective electromagnets comprising, a feeding timer having contact switches conductively connected with the respective electromagnets and a rotor for engaging said contact switches, a control timer having a contact switch conductively connected between said feeding timer and a source of electric energy and a rotor for engaging said control timer switch, means for driving said timer rotors, and automatic means for changing the relative angular positions of said timer rotors with respect to each other. 20
8. In an amusement device of the class described, the combination of: a deck having a plurality of lanes thereon; shafts rotatably supported adjacent the ends of said lanes; a plurality of aligned sets of pulleys mounted on said shafts in parallel relation with said lanes; a belt member extending over each set of pulleys; a racing piece in each lane attached to a corresponding belt member; means for rotating one of said shafts in a belt advancing direction; a plurality of clutch elements secured to said belt advancing shaft and normally out of engagement with the respective pulleys; electromagnetic means for individually engaging said clutch elements with their respective pulleys, and means for intermittently energizing the respective electromagnets comprising, a feeding timer having contacts conductively connected with the respective electromagnets and a rotor for engaging said contacts, a control timer having contacts conductively connected between said feeding timer and a source of electric energy and a rotor for engaging said control timer contacts, means for driving said timer rotors in timed relation with each other, and automatic means for changing the relative angular positions of said timer rotors with respect to each other, one of said timer rotors being designed to intermittently engage the corresponding timer contacts over unequal time intervals during a single revolution thereof. 25
9. For use in a racing game of the class described, the combination of: a rotatable shaft; means for rotating said shaft; a plurality of pulleys rotatably mounted on said shaft; a plurality of clutch members secured to said shaft and normally out of engagement with the corresponding pulleys; a plurality of electromagnets for actuating the pulleys into friction engagement with the respective clutch members; a plurality of circumferentially arranged contact feed switches conductively connected with the respective electromagnets; a rotor adapted to engage and close the respective switches; a control switch conductively connected with the respective feed switches and with a source of electrical energy; a second rotor associated with said control switch; a plurality of projections of different lengths mounted on said second rotor and adapted to engage said control switch; means for revolving said first and second rotors at a predetermined speed ratio with respect to each other; and means for mo- 30

mentarily locking one of said rotors during the continued rotation of the other of said rotors.

10. In an amusement device of the class described, the combination of: a deck having a plurality of lanes thereon; shafts rotatably supported adjacent the ends of said lanes; a plurality of aligned sets of pulleys rotatably mounted on said shafts in parallel relation with said lanes; a belt member extending over each set of pulleys; a racing piece in each lane attached to a corresponding belt member; means for rotating one of said shafts in a belt advancing direction; means for rotating the other of said shafts in a belt retracting direction; a plurality of clutch elements secured to said belt advancing shaft and normally out of engagement with the respective pulleys thereon; electromagnetic means for individually engaging said clutch elements with their respective pulleys; control means for repeatedly and intermittently connecting the respective electromagnets with a source of electric energy; retracting clutch elements secured to said retracting shaft and normally out of engagement with the pulleys thereon; retracting electromagnetic means for simultaneously engaging said retracting clutch elements with their respective pulleys; and means for simultaneously disconnecting the first named electromagnetic means from the source of electric energy and for energizing said retracting electromagnetic means.

11. In an amusement device of the class described, the combination of: a deck having a plurality of lanes thereon; shafts rotatably supported adjacent the ends of said lanes; a plurality of aligned sets of pulleys rotatably mounted on said shafts in parallel relation with said lanes; a belt member extending over each set of pulleys; a racing piece in each lane attached to a corresponding belt member; means for rotating one of said shafts in a belt advancing direction; means for rotating the other of said shafts in a belt retracting direction; a plurality of clutch elements secured to said belt advancing shaft and normally out of engagement with the respective pulleys thereon; electromagnetic means for individually engaging said clutch elements with their respective pulleys; control means for repeatedly and intermittently connecting the respective electromagnets with a source of electric energy; retracting clutch elements secured to said retracting shaft and normally out of engagement with the pulleys thereon; retracting electromagnetic means for simultaneously engaging said retracting clutch elements with their respective pulleys; and means including a switch actuated by any one of said advancing racing pieces at a predetermined point in its travel for simultaneously disconnecting the first named electromagnetic means from the source of electric energy and for energizing said retracting electromagnetic means.

12. In an amusement device of the class described, the combination of: a deck having a plurality of lanes thereon; shafts rotatably supported adjacent the ends of said lanes; a plurality of aligned sets of pulleys rotatably mounted on said shafts in parallel relation with said lanes; a belt member extending over each set of pulleys; a racing piece in each lane attached to a corresponding belt member; means including an electric motor for rotating said shafts in opposite directions; means for energizing said motor; clutch elements on one of said shafts adjacent each pulley thereon; electromagnetic means for causing each of said pulleys to intermittently and inde-

pendently engage its respective clutch element to individually turn said pulleys in a belt advancing direction; retracting clutch elements on the other shaft normally out of engagement with the corresponding pulleys; electromagnetic means for simultaneously causing said last mentioned pulley to engage said retracting clutch elements to rotate the pulley in a belt retracting direction; timing means for intermittently connecting the respective advancing electromagnetic means with a source of electric power; switch means actuated by any one of said advancing racing pieces at a predetermined point in its travel for simultaneously disconnecting said timing means from said source of power and energizing said retracting electromagnetic means; and a plurality of parallel switches actuated by the retracted racing pieces to disconnect said motor when all of said pieces are retracted to the ends of their respective lanes.

13. In an amusement device of the class described, the combination of: a deck; a plurality of racing pieces adapted for parallel movement along said deck; means for advancing each of said racing pieces, said means including a clutch means normally out of driving engagement for each of said racing pieces; electromagnetic means for individually operating each of said clutch means; timing means conductively connected with said electromagnetic means for intermittently connecting the respective electromagnetic means with a source of electric energy over varying intervals of time; means for simultaneously retracting all of said racing pieces, said means including electromagnetically controlled retracting clutch means; and switch means connected in circuit with a source of electric energy and with said electromagnetic clutch operating means and said electromagnetically controlled retracting clutch means and actuated by any one of said racing pieces at a predetermined point in its travel for simultaneously disconnecting all of said electromagnetic clutch operating means from the source of electric energy and for energizing said electromagnetically controlled retracting clutch means.

14. In an amusement device of the class described, the combination of: a deck; a plurality of racing pieces adapted for parallel movement along said deck; means for advancing each of said racing pieces, said means including a clutch means normally out of driving engagement for each of said racing pieces; electromagnetic means for operating each of said clutch means; timing means conductively connected with said electromagnetic means for intermittently connecting the respective electromagnetic means with a source of electric energy over varying intervals of time; means for simultaneously retracting all of said racing pieces, said means including electromagnetically controlled retracting clutch means; a plurality of electric lights corresponding to the respective racing pieces; switch means connected in circuit with a source of electric energy, with said electromagnetic clutch operating means, with said electromagnetically controlled retracting clutch means, and said electric lights, and adapted to be actuated by any one of said advancing pieces at a predetermined point in its travel for simultaneously energizing the electric light corresponding to the switch engaging racing piece, disconnecting said electromagnetic clutch operating means from the source of electric energy and at the same time energizing said electromagnetically controlled retracting clutch means.

15. In an amusement device of the class described, the combination of: a deck; a plurality of racing pieces adapted for parallel movement along said deck; means for advancing each of said racing pieces, said means including a clutch means normally out of driving engagement for each of said racing pieces; electromagnetic means for operating each of said clutch means; timing means conductively connected with said electromagnetic means for intermittently connecting the respective electromagnetic means with a source of electric energy over varying intervals of time; means for simultaneously retracting all of said racing pieces, said means including electromagnetically controlled retracting clutch means; switch means connected in circuit with a source of electric energy, with said electromagnetic clutch operating means and with said electromagnetically controlled retracting clutch means, and adapted to be actuated by any one of said advancing pieces at a predetermined point in its travel for simultaneously disconnecting said electromagnetic clutch operating means from the source of electric energy and at the same time energizing said electromagnetically controlled retracting clutch means; and means for disconnecting said electromagnetically controlled retracting clutch means from its source of electric energy; and a plurality of switches connected in parallel with a source of electric energy adapted to be engaged by the respective racing pieces as they are retracted to predetermined aligned points for operating said disconnecting means when all of said switches are engaged by their corresponding racing pieces.
16. In an amusement device of the class described, the combination of: a deck; a plurality of racing pieces adapted for parallel movement along said deck; means for advancing each of said racing pieces, said means including a clutch means normally out of driving engagement for each of said racing pieces; electromagnetic means for operating each of said clutch means; timing means conductively connected with said electromagnetic means for intermittently connecting the respective electromagnetic means with a source of electric energy over varying intervals of time; means for simultaneously retracting all of said racing pieces, said means including electromagnetically controlled retracting clutch means; switch means connected in circuit with a source of electric energy, with said electromagnetic clutch operating means and with said electromagnetically controlled retracting clutch means, and adapted to be actuated by any one of said advancing pieces at a predetermined point in its travel for simultaneously energizing the corresponding light switch relay, disconnecting said electromagnetic clutch operating means from the source of electric energy and at the same time energizing said electromagnetically controlled retracting clutch means; and means for disconnecting said electromagnetically controlled retracting clutch means from its source of electric energy; and a plurality of switches connected in parallel with a source of electric energy adapted to be engaged by the respective racing pieces as they are retracted to predetermined aligned points for operating said disconnecting means when all of said switches are engaged by their corresponding racing pieces; a solenoid means for actuating said relay switch locking means; and means for energizing said last mentioned solenoid means.
17. In an amusement device of the class described, the combination of: a deck; a plurality of racing pieces adapted for parallel movement along said deck; means for advancing each of said racing pieces, said means including a clutch means normally out of driving engagement for each of said racing pieces; electromagnetic means for intermittently connecting the respective electromagnetic means with a source of electric energy over varying intervals of time; means for simultaneously retracting all of said racing pieces, said means including electromagnetically controlled retracting clutch means; a plurality of electric lights corresponding to the respective racing pieces; relay switches connected with a source of electric energy for energizing the respective lights; locking means for holding each relay switch closed; switch means connected in circuit with a source of electric energy, with said electromagnetic clutch operating means, with said electromagnetically controlled retracting clutch means, and with said electric lights, and adapted to be actuated by any one of said advancing pieces at a predetermined point in its travel for simultaneously energizing the corresponding light switch relay, disconnecting said electromagnetic clutch operating means from the source of electric energy and at the same time energizing said electromagnetically controlled retracting clutch means; and means for disconnecting said electromagnetically controlled retracting clutch means from its source of electric energy; and a plurality of switches connected in parallel with a source of electric energy adapted to be engaged by the respective racing pieces as they are retracted to predetermined aligned points for operating said disconnecting means when all of said switches are engaged by their corresponding racing pieces; a solenoid means for actuating said relay switch locking means; and means for energizing said last mentioned solenoid means.
